CLAIM

The ornamental design for a chair component, as shown and described.

DESCRIPTION

FIG. 1 is a perspective view of a chair component showing my new design.

FIG. 2 is a front elevational view thereof.

FIG. 3 is another front elevational view thereof.

FIG. 4 is a right elevational view thereof.

FIG. 5 is a rear view thereof.

FIG. 6 is a left elevational view thereof.

FIG. 7 is a top view thereof.

FIG. 8 is a bottom view thereof.

FIG. 9 is a perspective view of a second embodiment of the chair component showing my new design.

FIG. 10 is a front elevational view of FIG. 9.

FIG. 11 is another front elevational view of FIG. 9.

FIG. 12 is a right elevational view of FIG. 9.

FIG. 13 is a rear view of FIG. 9.

FIG. 14 is a left elevational view of FIG. 9.

FIG. 15 is a top view of FIG. 9; and,

FIG. 16 is a bottom view of FIG. 9.

The broken lines in FIGS. 3 and 11 depict a chair and form no part of the claimed design.
